UNITED STATES PATENT OFFICE.

THOMAS A. RANDALL, OF NEW YORK, N. Y.

PUZZLE.

1,120,161.

Specification of Letters Patent.

Patented Dec. 8, 1914.

Application filed November 13, 1913. Serial No. 800,827.

To all whom it may concern:

Be it known that I, THOMAS A. RANDALL, a citizen of the United States, residing at 2067 Story avenue, New York city, in the 5 county of Westchester and State of New York, have invented certain new and useful Improvements in Puzzles; and I do declare the following to be a full, clear, and exact description of the invention, such as will enable others skilled in the art to which it 10 pertains to make and use the same.

This invention relates to games and toys, and more especially to puzzles; and the object of the same is to produce a device of 15 this kind in which an image made in the shape of a sitting or kneeling human figure is to be manipulated by shaking the casing or receptacle until the image assumes a desired position therein and the puzzle is 20 solved.

The invention consists also in the provision of an imitation chair within the receptacle and a path leading to the chair, and the puzzle may be solved by requiring that 25 the player shall agitate the casing until the image sits upon the chair.

The object is carried out by details hereinafter more fully described and claimed, and shown in the drawings wherein—
30 Figure 1 is a plan view of this improved puzzle, and Fig. 2 is a longitudinal section on the line 2—2 thereof. Figs. 3 and 4 are cross sections on the lines 3—3 and 4—4 of Fig. 1, and Fig. 5 is a perspective detail of 35 the plate and seat.

The numeral 1 in the drawings designates a box-like casing having a transparent top 2 of glass, mica, or possibly fine wire mesh, secured upon the upper edge of the casing in 40 any suitable manner as by a beading 3 and nails or tacks 4. The shape of the casing is unimportant, but it may well be rectangular as shown in the drawings and by preference I would make its bottom 5 flat so that it will 45 rest squarely on a table or other object, as seen in Figs. 3 and 4.

The numeral 6 designates a plate, preferably of metal and made rather thin, and this plate is secured in any suitable manner along 50 the bottom 5. One end of this plate is continued into an integral and narrow tongue 8 constituting what I call a "path," and the remote end of this strip or tongue of metal is bent into the shape of a seat or chair 9 as 55 best seen in Fig. 5. Finally one or more images 10 made in the shape of a sitting or

kneeling human figure as seen at the left of Fig. 2, are provided, and it is obvious that the configuration of this image or figure is such that it may kneel as there shown in full lines 60 or it might sit on the chair or seat 9 as indicated in dotted lines. As will be observed from Fig. 3, the sides of this image are rather flat so that it could lie on either side, to render the proper placing of the image 65 more difficult and the height of the interior of the casing or receptacle is such that it is quite possible for the image to be jiggled about therein to a considerable extent. Although but one image is shown, there may 70 be several, and they may be painted in different colors or made of different metals, as I prefer to make the images of metal in order to give them weight.

The object of the puzzle is to seat the 75 image on the chair, or perhaps the object would be to cause the image to kneel, or if there are two images the puzzle might be solved by seating one and causing the other to kneel at any proper point. The puzzle 80 will be solved by agitating the casing until the image is thrown off of the bottom and onto the path 8, and is moved along the same and takes its seat on the chair 9; and obviously this will be quite difficult to accomplish. 85

The parts are of the desired proportions and materials, excepting as hereinbefore mentioned, and details are obviously not essential. 90

What is claimed as new is:

1. A puzzle comprising a box-like casing having a transparent top, and an image loose therein and made in the shape of a combined sitting and kneeling human figure 95 having flat sides.

2. A puzzle comprising a receptacle having a transparent top, a seat within the receptacle, a pathway leading to said seat and an image loose therein and made in imitation of a sitting human figure and designed to be manipulated along said pathway onto 100 said seat.

3. A puzzle comprising a box-like casing having a transparent top, an image loose 105 within said receptacle and made in the shape of a sitting human figure, and a plate secured at one end within the receptacle and having its other end formed into the shape of a chair or seat. 110

4. A puzzle comprising a box-like casing whose top is transparent, a plate secured

across the bottom near one end of the same and continued thence into a narrow tongue, the remote end of said tongue being formed into the shape of a chair or seat, and an image loose within said receptacle and formed in the shape of a sitting human figure.

In testimony wherof I have hereunto set my hand in presence of two subscribing witnesses.

THOMAS A. RANDALL.
